VERNER LINDSJO, OF HOPEDALE, MASSACHUSETTS, ASSIGNOR TO DRAPER CORPORATION, OF HOPEDALE, MASSACHUSETTS, A CORPORATION OF MAINE

REED MOUNTING FOR LOOMS

Application filed March 25, 1931. Serial No. 525,073.

This invention relates to looms and is more particularly directed to the reed mounting whereby all lost motion between the reed and its supporting elements is avoided.

5 It is now the ordinary practice to support the reed for movement with the lay by mounting the upper and lower portions of the reed in the hand rail and lay beam respectively in order that when the lay beats up, the weft or filling thread may be driven accurately to the fell of the cloth. Lost motion may at times occur between the reed and its supporting elements and particularly is this noticeable in loose reed motions, where 10 the reed at times may swing about one of its supports should the shuttle become trapped in the shed to thereby prevent breaking of the warp threads.

15 One of the objects of the present invention is to provide means for taking up any lost motion that may occur between the reed and its supporting elements and especially in loose reed motions.

20 In accordance with the present invention the hand rail is provided with a longitudinal groove for receiving the upper reed bar or other dent holding means, and devices are provided whereby any lost motion that may occur between the reed and its supporting elements may be readily taken up, so that the reed itself shall effect the beating-up movement of the weft or filling threads accurately to the fell of the cloth. In these loose 25 reed motions wherein the locking bar rests upon the lower reed bar it is especially desirable that all lost motion be prevented, as otherwise the reed itself may be injured and the beat-up improperly made.

30 The invention and novel features will best be made clear from the following description and accompanying drawings of one good form thereof.

35 In the drawings:—

40 Fig. 1 is a rear perspective view of a reed mounting containing the present invention; Fig. 2 is a cross section through the reed and its supporting elements; and Fig. 3 is a front view of a portion of the hand rail showing one form of the present 45 invention.

In the drawings a loose reed motion is illustrated as one embodiment of the present invention, but it is to be understood that the advantages of the invention may be realized in other forms of reed mounting.

55 The lay beam 1 may be of usual construction and as herein shown it has a cut-away portion 2 at the rear thereof to receive the lower bar 3 of the reed 4, and as now common in loose reed motions the lower portion 60 of the reed is held in the recess 2 by a locking bar.

55 The locking bar 5 for the reed in the present instance of the invention is so related to the lay beam and reed that it rests against the lower reed bar 3 and in some cases a bearing portion 6 of the locking bar may rest upon the rear surface of the reed dents.

60 The locking bar 5 is supported by arms 7 which are themselves mounted upon the rock 70 shaft 8 secured in suitable bearings 9 extending downwardly from the lay beam and a spring 10 normally tends to move the locking bar 5 into its locking position as indicated in Figs. 1 and 2. This spring 10, as 75 shown, is of the spiral type mounted upon the rock shaft 8 and one end of the spring is secured at 11 to one of the rock shaft bearings 9, as indicated in Fig. 1, while the opposite end of the spring is secured to the rock 80 shaft 8 by means of the collar 12, which itself may be secured adjustably to the rock shaft. The features so far described may be of usual construction, it being understood that should the shuttle get trapped in the shed the locking bar 5 may yield to prevent breaking of 85 the warp threads, as usual.

90 Extending above the lay beam 1 are the supporting arms 13, which are preferably located one at each end of the lay beam and may be constituted by portions rising from the usual lay swords. The supporting arms 13 carry the hand rail 14, the lower portion of which in the present instance is provided with a reed bar retaining groove 15, in which 95 the upper reed bar 16 is seated.

95 It is now the common practice to provide hand rails for reed mountings of a standard character, so that when the reed and hand rail are to be assembled the upper reed bar 100

16 is inserted longitudinally into the reed bar retaining groove 15, while the reed dents extending downwardly from the reed bar through an opening 17 communicate with the 5 reed bar retaining groove and it will be obvious that should any lost motion occur between the reed and its mountings that injury to the reed dents may result, and proper beat-up of the weft or filling threads be not accomplished.

The present invention, therefore, provides that the hand rail 14 may be sustained by the supporting arms 13 for rotative movement about a longitudinal axis and be secured in 15 such rotative position by clamping means as will presently appear, with the result that turning movement of the hand rail about its longitudinal axis causes all lost motion between the reed and its mountings to be eliminated and the reed held rigidly in position 20 during beat-up.

Each of the supporting arms 13 is provided with a bearing face 18 and extending through the supporting arms and the hand rail are the 25 clamping bolts or similar devices 19, which serve to hold the hand rail rigidly in position.

In order that the hand rail may be conveniently turned about a longitudinal axis, a 30 fulcrum lug is interposed between the bearing face 18 of the supporting arms 13 and the adjoining face of the hand rail.

In the present instance of the invention the bearing lugs 20 are constituted by plates secured as shown to the rear face of the hand rail 35 14 and the lower portion of the plates is somewhat enlarged or thickened.

Above the secured bolts 19 are the rail turning devices which in the present instance 40 of the invention consist of adjusting screws 21, which extends through the upper portion of the hand rail, and at the front thereof such adjusting screws are provided with a notched counter sunk head 22 that may be readily turned by means of a hand implement when adjustment of the hand rail about the longitudinal axis formed by the fulcrum lugs becomes desirable. The adjusting screws 21, as shown in the present instance, have their 45 rear end portions 23 bearing upon the upper part of the face 18 of the supporting arms, with the result that by loosening the securing bolts 19 through the wing nuts 24 the adjusting devices 21 may be turned in either direction to thereby rotate or turn the hand rail 14 to the desired position and prevent lost motion between the reed and its supporting elements, and when the adjustment has been effected the wing nuts 24 may be tightened 55 and the hand rail held in its new rotative position.

From the construction described it will be evident that the present invention provides a simple, effective and accessible means 60 for turning the hand rail 14 about a longitudi-

nal axis, formed in the present instance by the fulcrum lugs 20 to thereby take up any slack or lost motion that may exist between the reed and its supporting elements, so that the reed dents themselves at the upper portion of the reed will bear firmly against the sides of the openings 17 leading into the longitudinal groove 15 of the hand rail.

What is claimed is:

1. In a loom, a reed mounting, comprising, in combination, the lay beam, a hand rail having a longitudinal groove, a reed mounted in the longitudinal groove of the hand rail, and adjusting means for turning the hand rail about a longitudinal axis to take up lost motion between the hand rail and reed.

2. In a loom, a hand rail mounting for loose 85 reed motions, comprising, in combination, the lay beam, a hand rail having a longitudinal groove, a reed having its upper bar mounted in the longitudinal groove of the hand rail, and means for turning the hand rail about a longitudinal axis to take up slack between the hand rail groove and reed, and devices for securing the hand rail in any position to which it may be turned by said means.

3. In a loom, the combination of the lay beam, a hand rail having a reed holding 95 groove, supporting arms for the hand rail, a fulcrum lug between the hand rail and supporting arms, bolts for securing the hand rail to the supporting arms, and means for adjusting the hand rail about the fulcrum 100 lugs as a centre to take up lost motion between the hand rail and reed.

4. In a loom, a hand rail mounting for loose reed motions, comprising, in combination, a lay beam, a hand rail having a longitudinal groove, a reed having the upper 105 reed bar mounted in said groove, a reed locking bar for holding the reed to the lay beam during beat up, means for turning the hand rail about a longitudinal axis to take up lost motion between the hand rail and reed, and means for securing the hand rail in adjusted 110 position.

5. In a loom, a hand rail mounting, comprising, in combination, the lay beam, a hand rail for the upper reed bar, supporting arms for the hand rail, an adjusting device for turning the hand rail about a longitudinal axis with respect to the hand rail supporting 115 arms, and means for securing the hand rail in any adjusted position about its longitudinal axis to take up any lost motion between the reed and hand rail.

6. In a loom, a reed mounting, comprising, in combination, the lay beam, a hand rail having a longitudinal groove, a reed having its upper bar in said groove, an adjusting screw for turning the hand rail about a longitudinal axis to take up lost motion between the groove of the hand rail and reed,

and clamping screws for securing the hand rail in its rotative adjustment.

7. In a loom, the combination of the lay beam, a hand rail having a longitudinal reed bar retaining groove, a reed having its upper portion in said longitudinal groove, supporting arms for the hand rail, clamping devices for securing the hand rail to said supporting arms, a fulcrum lug between the 10 hand rail and supporting arms about which the hand rail may be turned on a longitudinal axis, and adjusting devices between the hand rail and supporting arms for turning the hand rail about the fulcrum lugs as a 15 centre.

In testimony whereof, I have signed my name to this specification.

VERNER LINDSJO.
